(57) **CLAIM**

The ornamental design for dental floss dispenser, as shown and described.

DESCRIPTION

FIG. 1 is a front view of the dental floss dispenser;
 FIG. 2 is a back view of the dental floss dispenser;
 FIG. 3 is a left-side view of the dental floss dispenser;
 FIG. 4 is a right-side view of the dental floss dispenser; and,
 FIG. 5 is a top view of the dental floss dispenser.

The broken lines shown in FIG. 5 are for illustrative purposes only and form no part of the claimed design.
